DECORATIVE DOOR KNOBS

Walter S. Scott, Pasadena, Calif.; Anna Marie Scott, executrix of said Walter S. Scott, deceased

Application February 18, 1957, Serial No. 640,642

2 Claims. (Cl. 292—347)

The invention relates to decorative knobs and more particularly to transparent door knobs for use in combination with door latches and locks.

Transparent door knobs are particularly desirable in the modern home interiors because of their chaste appearance which harmonizes well with the Spartan modern decorations. Because of their transparency such knobs appear to be suffused with adjacent colors. When used with highly polished or colored door lock cartridges, the transparent door knob takes on the coloration of the cartridge.

It has been found that the appearance of the door lock cartridge within the transparent knob is enhanced if the surfaces of the cartridge are spaced slightly from contact with inner surfaces of the knob. Thus the interior surfaces of the knob containing the cartridge are conventionally dimensioned so that only a small portion of the inner surface of the knob is in contact or engaged with the lock cartridge.

Conventionally, access to the lock cartridge must be provided in the surface of the knob remote from the door. An access port accommodates the lock buttons or the keys which operate the door lock. The problem introduced by the access port is that the conventionally polished face of the lock cartridge which contributes so much of the decorative appearance of transparent knobs is marred when foreign particles enter by way of the access port and deposit on the flange face.

I have invented a simple and economical apparatus having all of the decorative advantages of transparent door knobs and which obviates the disadvantage of the entry of foreign particles into the interior of the knob. The invention may be embodied in a decorative transparent knob for use with a door latch and lock having a lock cartridge with a substantially planar flange face oriented toward the surface of the knob remote from the door. The knob comprises a body having an inner cylindrical wall defining a lock cartridge cavity having an inner end wall transverse to the long axis of the cartridge. An access port connects to the outer surface of the knob remote from the door and opens through the end wall of the cavity. The access port is smaller than the cartridge cavity. The knob has means for spacing the flange face of the lock cartridge from the transverse end wall and for sealing the space between the flange face and the transverse end wall against the entry of foreign particles through the access chamber.

Preferably the spacing and sealing means of the knob comprises an annulus formed integrally with the knob adjacent the access port. The annulus may be concentric with the port and projects inwardly to the cartridge cavity beyond the transverse end wall to make sealing contact with the flange face of the lock cartridge. The extreme diameter of the annulus obviously must be smaller than the extreme diameter of the flange face so that a substantial area of the face affords a reflective surface not in contact with the interior surfaces of the transparent knob.

2

Further advantages of the invention are apparent in the following detailed description and drawing in which:

Fig. 1 is a fragmentary elevation partly broken away and showing a transparent knob used with a door lock and latch;

Fig. 2 is a fragmentary sectional elevation taken along line 2—2 of Fig. 1; and

Fig. 3 is a fragmentary elevational view partly in section showing a transparent knob used with a door lock of the barrel type.

In Figs. 1 and 2 a door 10 having an escutcheon plate 12 from which a door knob shaft 14 projects is provided with a decorative transparent knob 15 used with a door lock 17. The door lock is of the type having a lock button 19 projection from a face 21 of the knob remote from the door.

The mechanism of the lock is contained within a door lock cartridge 23. The cartridge resides within the knob in a cartridge cavity 25 defined by an inner wall 26 of substantially cylindrical configuration. The cartridge cavity terminates in a transverse end wall 28 remote from the door. Preferably the lock cartridge has a polished exterior. The exterior may be tinted or the finish may be a chromium or other decorative plate whose coloration is enhanced by the transparent door knob. The cartridge of Fig. 1 has a flange face 31 oriented toward the surface of the knob remote from the door. The flange face is preferably concentric to the center of the knob and an access port 33 which connects between the exterior of the knob and the cartridge cavity.

The lock button 19 extends coaxially through the access port, projecting beyond the flange face a sufficient distance for easy operation by someone manipulating the door lock.

As mentioned above, the decorative effect of the flange face is greater if the face is not in contact with the interior surfaces of the knob. This is found to be especially true if the knob is made from transparent or translucent plastic such as Lucite. Therefore, the preferred embodiment of the invention has an annulus 35 concentric with the access port and extending into the cartridge cavity beyond the transverse end wall. The annulus butts against the flange face of the cartridge in the area adjacent the smaller diameter of the flange. The extreme diameter of the annulus is less than the comparable diameter of the flange so that a small annular volume 36 is defined between the transverse end wall and the flange face. The lock cartridge may be fixed within the knob by means such as those described in applicant's Patent No. 2,679,913, issued June 1, 1954. This method and like methods insure that the cartridge is fixed within the knob to permit turning the latch and so that its position against the innermost face of the annulus does not vary. This contact between the annulus and flange face seals the space between the face and the end wall so that no foreign particles entering through the access port may lodge in the volume defined thereby.

Therefore, the annulus performs the functions of a spacer and a seal.

The invention may be embodied in a door knob used in combination with other types of locks and latches in which a lock and latch cartridge resides within the knob. Fig. 3 illustrates transparent knob 41 used in conjunction with a barrel lock 42 having a substantially cylindrical lock cartridge 44. The lock cartridge must be considerably larger than the cartridge for a button operated lock in order to contain the tumblers and other components of the lock.

The knob of Fig. 3 has an access port 46 substantially coaxial with the lock cartridge. The access port connects the exterior face 48 of the knob remote from the door

with a cartridge cavity 51 defined by a substantially cylindrical wall 53. The cartridge cavity is terminated at its end remote from the door by a transverse end wall 55. The access port extends through this end wall.

The cartridge has a flange face 57 oriented toward the surface 48 of the knob. This flange face is spaced from the end wall and sealed from the access port by an annulus 59 similar in construction and function to the annulus 35 of Figs. 1 and 2. The annulus outer diameter is kept to a minimum so that full decorative advantage may be derived from the larger flange face of the lock cartridge.

The inventive concept is adaptable to many types of locks and latches apart from those illustrated. Transparent knobs of decorative aspect may thus be used in many situations without the drawbacks in like conventional devices.

I claim:

1. A transparent knob for use with a door latch and lock having a lock cartridge with a substantially planar flange face oriented toward the surface of the knob remote from the door, the knob comprising a body, an inner cylindrical wall, an inner end wall transverse to the longitudinal axis of the cartridge, said walls defining

a lock cartridge cavity within the body, an access port connecting to the outer surface of the knob remote from the door and opening through the end wall of the cavity, the access port being smaller than the cartridge cavity,

5 and means for spacing the flange face of the lock cartridge from the transverse end wall to form a volume therebetween, and means for sealing the space between the flange face and the transverse end wall against the entry of foreign particles through the access chamber.

10 2. Apparatus in accordance with claim 1 in which the means for spacing the flange face and the means for sealing the space between the flange face and the transverse end wall comprises an annulus of a lesser outer diameter than the extreme diameter of the flange face 15 formed integrally with the inner end wall and projecting inwardly therefrom for sealing contact with the flange face.
